US00D518445S

(12) **United States Design Patent** (10) Patent No.: **US D518,445 S**
(45) Date of Patent: **** Apr. 4, 2006**

(54) **ELECTRICAL CONNECTOR**

(75) Inventor: **Chia-Hao Fan**, Tu-Cheng (TW)

(73) Assignee: **Hon Hai Precision Ind. Co., Ltd.**,
Taipei Hsien (TW)

(**) Term: **14 Years**

(21) Appl. No.: **29/233,404**

(22) Filed: **Jun. 30, 2005**

(30) **Foreign Application Priority Data**

Mar. 25, 2005 (TW) 94301660

(51) **LOC (8) Cl. 13-03**

(52) **U.S. Cl. D13/147**

(58) **Field of Classification Search** D13/146,
D13/147, 184, 199; 439/74, 79, 83, 108,
439/181, 607-610, 637, 638

See application file for complete search history.
